WIRE FORMING APPARATUS

Ralph Calmy, Las Vegas, Nev., assignor, by direct and mesne assignments, to Dannie O. Malafouris, Portland, Oreg.

Filed Aug. 29, 1955, Ser. No. 531,147

2 Claims. (Cl. 153—66)

This invention relates to wire forming apparatus. It pertains particularly to apparatus for forming wire of substantial gauge into spirals which may be intermeshed with each other to form a continuous wire screen.

In making fireplace screens and like products it heretofore has been the practice to pass wire of substantial gauge through a die which forms it into a spiral of predetermined pitch. When the spiral has reached the desired length, the apparatus is stopped and the spiral is cut off.

The spiral then is held in suitable apparatus and placed in such a position that upon passing a further quantity of wire through the die the resulting second spiral is intermeshed as it leaves the die with the first spiral. When the second spiral has reached the selected length, it also is cut off. This process is repeated until a screen of the desired dimensions has been built up.

Numerous difficulties are, however, inherent in the above described procedure. In the first place, means have not been available for arresting the passage of the wire through the die at the precise instant when the selected length of wire has passed through it. As a consequence, the spiral units of which the screen is composed are of unequal length and must be trimmed. This obviously is a time consuming and wasteful operation.

Also, efficient means have not been available for adjusting the wire forming apparatus so that it can produce spirals of a selected length over a wide range of lengths. Still further, the dies which have been employed in apparatus of this class have been subject to mutilation and rapid wear by the action of heavy gauge wire passing rapidly through them.

Accordingly, it is the object of the present invention to provide wire forming apparatus characterized by the following objects and advantages:

First, it measures accurately the length of each spiral formed, eliminating a substantial trimming waste.

Second, it can be adjusted easily and rapidly to form spirals of any desired length between wide limits.

Third, it is several times more rapid in operation than is prior art apparatus of this class.

Fourth, it produces spirals of uniform pitch over a long operating period.

Fifth, its operation is smooth, in spite of the stiffness of the wire which it handles.

Sixth, it is easily adjustable for threading the wire through the apparatus at the start of each operation.

Seventh, it provides means for holding a forming die securely, which means, however, are easily adjustable for exchanging or replacing dies as required by changes in wire gauge, spiral pitch, etc.

Eighth, it provides means for minimizing wear on the die caused by passage of the wire therethrough.

Ninth, it does not mutilate the wire used in forming the screen.

Tenth, it is attachable to, and operable in conjunction with, work holding apparatus of the class commercially available for weaving the spirals together in the production of fireplace and other mesh screens.

2

The manner in which the foregoing and other objects of this invention are accomplished will be apparent from the accompanying specification and claims, considered together with the drawings, wherein:

5 Fig. 1 is a view in side elevation of the herein described wire forming apparatus;

Fig. 2 is an enlarged fragmentary view, partly in section, of the die used in the herein described wire forming apparatus;

10 Fig. 3 is a sectional view, taken along line 3—3 of Fig. 2;

Fig. 4 is a detail, fragmentary view in section illustrating means which may be employed for opening and closing the cooperating drive rolls employed for feeding

15 wire through the herein described apparatus;

Fig. 5 is a detail view in elevation of mechanism which may be employed in determining the length of the spiral sections formed by the presently described apparatus; and

20 Fig. 6 is a circuit diagram illustrating a circuit which may be employed in the control of the apparatus.

Generally stated, the herein described wire forming apparatus comprises die means dimensioned for forming

25 wire into a spiral of the desired pitch when the wire is forced through the die. Drive means are provided for

driving the wire through the die means. Drive control

25 means also are provided for arresting or otherwise affecting the drive means when a predetermined length of wire has been formed into a spiral.

Also, means are provided for adjusting the drive means

30 to enable threading wire through the apparatus at the start of each operation with facility. Further, means are

provided for adjusting the drive control means so that the

35 length of the spiral sections may be varied between wide

limits simply and easily. Still further, a die is provided

upon which includes means for minimizing the wear attendant

upon passing heavy gauge wire through the die at high

velocity.

Considering the foregoing in greater detail and with

particular reference to the drawings:

The drive

The drive unit for the herein described wire forming apparatus is mounted on a frame indicated at 10. A

45 motor 12 is mounted at the base of the frame. Its shaft

mounts a pulley 14 which carries a belt 16, which, in turn,

drives a pulley 18 on clutch 20. Clutch 20 may be of

conventional construction and is operated by means of

a clutch collar 22.

50 A drive shaft 24 is mounted in bearings 26, 28 and is driven through clutch 20. This shaft drives the feeding

means for forcing the wire through the forming die. To

this end it has rigidly affixed to it a gear 30 which drives

a secondary drive shaft 32 through the meshing gear 34.

55 Shaft 32 is mounted for rotation in self aligning bearings 36, 38. Bearing 36 is mounted on an extension 40

of frame 10. Bearing 38 is mounted in a block 42 which

in turn is slidably mounted in a slot 43 (Fig. 4) in the

front frame member, thereby floating the bearing unless

60 it is locked in position by suitable means.

Shafts 24, 32 carry at their respective forward ends

drive wheels 44, 46. Wheel 44 has in its peripheral sur-

face a pair of spaced grooves 48, 50 while wheel 46 has

in its peripheral surface a corresponding pair of spaced

grooves 52, 54.

As is apparent particularly from Fig. 2, the peripheral

surfaces of wheels 44, 46 are closely adjacent each other

and grooves 48, 50 in the upper wheel are aligned and

in substantial registration with grooves 52, 54 in the

70 lower wheel. Also, since a one to one gear ratio may be

present between gears 30, 34, the wheels rotate at identical

speeds. Accordingly, a wire 56 may be fed through a

suitable wire guide 58, lubricated with oil through conduit 60, fed between wheels 44, 46, and driven thereby through a die to be described hereinafter.

Means also are provided for separating drive wheels 44, 46 in order to feed a wire therebetween with greater facility at the start of each operation. In the illustrated embodiment, such means comprise a cam 62 illustrated in Fig. 4.

Cam 62 is mounted on a shaft 64 supported between frame extensions 66, 68. It is operated by means of a lever 70 which is releasably connected through spring 72 with another frame extension 74.

The working surface of cam 62 engages a pin 76 which is slidable in an opening through frame member 78, and which abuts against the upper surface of block 42. As has been indicated above, this block is slidably mounted in opening 43 of frame 10 and carries the self-aligning bearing 38 by means of which one end of secondary drive shaft 32 is supported.

Block 42 in turn is supported through a compression spring 80, one end of which presses against the lower surface of block 42 and the other end of which presses against the frame of the apparatus. Accordingly, during normal operation of the apparatus, lever arm 70 is in a depressed position as indicated in solid outline in Fig. 4. It is held resiliently in this position by the action of spring 72.

When it is desired to separate feed rolls 44, 46, as when introducing wire therebetween, one end of spring 72 is released from the member to which it is attached, whereupon lever arm 70 assumes the dotted outline position of Fig. 4. In this position the action of cam 62 permits elevation of block 42, and hence of feed roll shaft 38 which it supports, through the action of compression spring 80. Wire 56 then may be threaded between the rolls and positioned in a selected opposed pair of peripheral grooves 48-54. Thereafter lever 70 may be returned to its Fig. 4 full outline position and spring 72 reconnected to it. The drive wheels then are ready for feeding wire through the apparatus.

The drive control

As has been indicated hereinabove, it is one of the primary features of the presently described wire forming apparatus that its operation can be adjusted to form accurately predetermined lengths of spiraled wire over a wide range of spiral lengths. The means for accomplishing this purpose are illustrated in Figs. 1, 5 and 6. In general, they comprise means for arresting the motion of drive wheels 44, 46 after a predetermined operation thereof.

To this end there is provided on drive shaft 24 a gear 90. This gear meshes with a gear 92 carried by shaft 94 of gear box 96. Gear box 96 is supported on the frame of the apparatus and is of the class by means of which a stipulated rate of rotation of shaft 94 may be translated into any desired rotational speed of gear box shaft 98. Shaft 98 then is used to operate means for arresting the motion of the drive wheels.

Such means may include a cam 100 having on its surface a projection 102 (Fig. 5). As the cam is rotated by shaft 98, its surface engages a wheel 104 carried by a spring pressed plunger 106 of an electric switch 108.

Switch 108 is in an electric circuit with a solenoid 110, which also is mounted on the frame 10 of the apparatus. This circuit is illustrated in Fig. 6. Electric power from a suitable source passes through line 112, switch 108, line 114, solenoid 110, and return line 116. A master switch 118 also may be included in parallel in the circuit, for turning the solenoid on and off and for use in emergency.

Accordingly, solenoid 110 may be energized by the action of cam 100 after a time interval determined by the setting of gear box 96. This timing in turn will de-

termine the length of the spiral sections formed by the apparatus.

Energization of solenoid 110 may be used for arresting the motion of the drive rolls, suitable means for accomplishing this purpose being as follows:

A link 120 interconnects the solenoid 110 with one end of a latch member 122. The other end of the latch member is pivotally connected to frame 10 through pin 124. An arm 126 extends outwardly from the latch and abuts against a stop 128. A compression spring 130 is interposed between frame member 10 and arm 126 to urge the arm, and hence latch 122, in a counterclockwise direction as viewed in Fig. 1. This action is opposed and overcome by the action of solenoid 110 when it is energized. Hence the latch is shiftable between two positions and this motion may be used for engaging and disengaging clutch 20.

Various linkages may be employed for achieving this result. In the illustrated linkage, a foot lever 132 is pivotally mounted intermediate its ends on a frame extension 134. The rear end of this lever is pivotally connected to link 136 which in turn is pivotally connected to link 138. The upper end of the latter link is pivotally connected to one arm 140 of a bell crank lever 142. The other arm 144 of the bell crank lever is connected to clutch collar 22, by means of which the clutch is operated.

A spring 146 interconnects arm 144 and frame member 148. Its action is such as to urge clutch collar 22 continuously and resiliently to the right as viewed in Fig. 1, this being the position of clutch disengagement.

A cross link 150 is pivotally connected at one of its ends to link 138 and adjacent the other of its ends to one of the frame members. A projecting segment of the cross link is formed with a notch 152 dimensioned for reception of latch 122.

Thus when foot lever 132 is depressed until it reaches the operating position of Fig. 1, links 136, 138 are elevated, moving arm 144 of bell crank lever 142 clockwise and engaging clutch 20. At the same time, the notched end 152 of cross link 150 is lowered to a position wherein spring 130 will advance latch 122 into engagement with the notch, solenoid 110 being de-energized.

After cam 100 has made one complete revolution, solenoid 110 will be energized. Thereupon, acting through rod 120, it withdraws latch 122 from engagement with the notched end of cross link 150. This enables spring 146 to move arm 144 of bell crank lever 142 in a counterclockwise direction, disengaging clutch 20. It also moves links 138, 136 downwardly and elevates foot operated lever 132 to its dotted outline position. These actions, i.e. the actions occurring upon completion of an operating cycle and disengagement of latch 122, are indicated by the arrows in Fig. 1.

The die

Positioned adjacent drive wheels 44, 46 at the outfeed side thereof is the die assembly indicated generally at 160. The construction of this assembly is illustrated in detail in Figs. 2 and 3. It comprises a housing 162 having extending outwardly therefrom a plug 164 dimensioned to fit into an opening in one of the members comprising frame 10, where it is secured by means of set screw 166. Housing 162 has a horizontal opening therethrough which is dimensioned for the reception of a die holder or casing 168.

The die holder is fixed in position by means of set screw 170. It is drilled to provide two spaced, longitudinal channels 172, 174. The spacing between these channels is such that they register with the opposed channels 48-54 on drive wheels 44, 46.

Casing 168 has therein a longitudinal recess dimensioned to receive a die 180, which is secured in the casing by means of set screw 182. The die is cylindrical in

shape and has on its peripheral surface spirally formed channels 184, 186. These are dimensioned to receive slidably wire of the selected gauge. Their infeed terminals register with channels 172, 174 through the casing.

Thus there is formed a pair of continuous passageways including the opposed pairs of grooves in drive wheels 44, 46, channels 172, 174 through the die holder, and spiral passageways 184, 186 along the periphery of die 180. When wire is forced through one or the other of these passageways, it is bent in a spiral corresponding to the shape of the passageways of the die surface.

Since there is a very substantial thrust developed by the wire as it is forced through the die assembly, means are provided to protect the component members of the assembly from wear and abrasion as well as to protect the wire itself from mutilation. Such means include a bearing collar or sleeve 190 contained in the outer portion of the recess in housing 162 and rotatably mounted about die 180. Its inner end abuts the end of die holder 168. Its outer end abuts against a hollow keeper or retaining member 192. The latter in turn is supported adjustably by means of a bracket 194 attached through adjustment slot 196 to housing 162 by means of bolt 198.

Accordingly when a new die is to be inserted in the apparatus, it is secured in die holder 168, its outer end encircled with bearing collar 190, and keeper 192 applied snugly but without preventing rotation of the collar. Then when wire is passed through the die, it engages the inner surface of bearing collar 190 with considerable force, causing the collar to rotate at a speed determined by the speed of movement of the wire. As a consequence, wear on the die assembly and mutilation of the wire are kept at a minimum.

Operation

The operation of the herein described wire forming apparatus is as follows:

Lever 70 on cam 62 is elevated to allow spring 80 to raise shaft 32, and hence separate wheels 44, 46. Wire 56 then is fed between the wheels along a path defined by selected channels 48—54 in the wheels, openings 172, 174 in the die holder 168, and channels 184, 186 in die body 180. Lever 70 then is depressed and maintained resiliently in position by attaching an end of spring 72 to it.

Gear box 96 next is set at the desired ratio and motor 12 started. The motor runs continuously, driving shaft 24 through clutch 20. Foot lever 132 then is depressed. This engages clutch 20 and initiates rotation of drive shaft 24 and of secondary drive shaft 32 which is coupled thereto through meshing gears 30, 34. Hence drive wheels 44, 46 on the drive shafts are driven at equal, substantially uniform rates and force the wire through the die, where it is formed into a spiral having a pitch determined by the pitch of the channels on the die.

As the first spiral is formed, it extends outwardly from the apparatus and is suitably supported. Its length is determined by the setting of gear box 96. As drive shaft 24 rotates, it drives shaft 94 on gear box 96 through meshing gears 90, 92. Shaft 98 of the gear box thereupon is rotated rapidly or slowly depending upon the setting of the box. Cam 100 on the end of shaft 98 is rotated correspondingly. Then when projection 102 on the cam contacts roller 104 on plunger 106 of electric switch 108, the switch is closed, energizing a circuit including solenoid 110.

Acting through rod 120, the solenoid moves latch 122 to the right as viewed in Fig. 1 against the compression of spring 130, until arm 126 abuts against stop 128. Cross link 150 thereupon no longer is restrained by the latch, and spring 146 acts to move arm 144 of bell crank lever 142 in a counterclockwise direction, disengaging the clutch and elevating foot pedal 132. Hence the drive stops almost immediately, although there is sufficient

momentum to carry the projection on cam 100 past roller 104, i.e. to the position of Fig. 5, where it is ready to start another cycle.

After the spiral has been formed, it is severed with knife 200. It then is elevated slightly in the holding apparatus in which it is contained until the axis of the spiral is substantially aligned with die 180. A second cycle of operation is initiated by depression of foot lever 132 whereupon another length of wire is formed into a spiral of identical length and pitch to the first length. In addition, it is intermeshed with the first length as it is formed so that a section of screen or wire mesh is built up. This process is repeated as often as is necessary to give a final screen 202 of the desired dimensions.

Hence it is apparent that by the present invention I have provided wire forming apparatus which forms wire into spirals of selected length and predetermined pitch rapidly and accurately. In addition, the length of the spiral produced may be easily adjusted over a wide range 20 by suitable adjustment of the drive, and its pitch readily varied by exchanging dies. Also, the spirals are formed without excessive wear on the die and without mutilation of the wire of which the spirals are composed.

Having thus described my invention in preferred embodiments, I claim:

1. Wire forming apparatus comprising a frame, a die assembly on the frame comprising a housing, a die holder mounted in the housing and having a forward longitudinal bore and a rearward closed end portion, a wire receiving opening in the closed end portion of the holder registering with the rearward end of the bore adjacent the periphery of the bore, a die body positioned removably in the die holder and projecting forwardly therefrom and having a spiral passageway about its periphery 35 registering with the wire receiving opening in the die holder, a bearing sleeve mounted freely within the housing adjacent the forward end of the die holder and freely encircling the forward projecting portion of the die body and dimensioned for frictional engagement and rotation 40 with wire passing through the passageway in the die body, a hollow keeper, keeper support means mounted removably on the housing for supporting the keeper adjacent the forward end of the sleeve, the opening in the keeper forming an axial extension of the opening in the bearing 45 sleeve, drive means on the frame for forcing wire through the wire receiving opening and the spiral passageway in the die body, clutch means in said drive means for controlling operation of the latter, movable link means on the frame and engaging the clutch means for moving the latter between engaging and disengaging positions, 50 manually operated lever means on the frame connected to the link means for moving the clutch means to engaging position, solenoid operated lock means connected to the link means for selectively locking the link means 55 in clutch-engaging position and for releasing the link means to disengage the clutch, the solenoid having an electric circuit including a switch, and switch actuating means operated synchronously by the drive means and operable after a predetermined operating cycle of the 60 drive means to effect release of the link means and disengagement of the clutch means.

2. Wire forming apparatus comprising a frame; die means mounted on the frame; a bearing sleeve rotatably mounted about the die means and in frictional engagement with the wire passing therethrough; a pair of drive wheels positioned about the die means for forcing wire through the die means; drive means for the drive wheels; a clutch in the drive means for controlling operation of the latter; pivotally mounted link means on the frame 70 engaging the clutch and movable between a locked position and a released position for holding the clutch in its engaging and disengaging positions, respectively; a manually operated lever on the frame connected to the link means for moving the link means to its locked position;

a solenoid having a movable member and an electric circuit; a switch in the electric circuit; lock means connected to the movable member of the solenoid and releasably engaging the link means for securing the latter in locked position, the lock means comprising a cross link pivotally mounted on the frame and engaging the link means, a spring pressed latch pivotally mounted on the frame and connected to the movable member of the solenoid, the latch being engageable with the cross link upon movement of the manually operated lever to locked position, the latch being disengageable from the cross link upon movement of the movable member of the solenoid to unlocked position, thereby releasing the link means for movement to disengage the clutch; and a cam driven synchronously by the drive means, the cam being arranged to engage the switch at the completion of a wire forming cycle to move the movable member of the sole-

noid and release the link means from its locked position, thereby disengaging the clutch.
